United States Patent Office.

C. D. READ, OF BURLINGTON, VERMONT.

Letters Patent No. 66,390, dated July 2, 1867.

IMPROVED BED-BOTTOM.

The Schedule referred to in these Letters Patent and making part of the same.

TO ALL WHOM IT MAY CONCERN:

Be it known that I, C. D. READ, of Burlington, in the county of Chittenden, and in the State of Vermont, have invented certain new and useful improvements in Spring-Bed Bottoms; and do hereby declare that the following is a full, clear, and exact description thereof, reference being had to the accompanying drawings, and to the letters of reference marked thereon, making a part of this specification:

In the annexed drawings, A A represent a series of horizontal slats, which are placed at suitable distances apart, and of a size to suit the length of the bedstead. B B represent two cross-rails, one placed near the head, and the other near the foot of the bed, and which are provided with coil-springs, such as are commonly used in spring-bed bottoms. One of these springs, C, is placed under each rail A, and firmly attached to the cross-pieces B. Each of the slats A A is provided with a circular block of wood or metal on its under side, which fits neatly into the contracted tops of the coil-springs C, as shown in Figure 2, thereby assisting the strength of the spring, and forming a substantial connection for the slats. Upon the cross-pieces B B are placed two nails, x x, with hooks formed at the top for connecting the lower round of the spring to the rail. Two of these hooked nails are first secured in the rail on each side of the spring, so that it is only necessary to pass the end of said spring under the first nail, and screw around until the hooks of each nail are caught over the coil. d d represent hooked nails placed each side of the spring upon the rails E, and to which are connected leather or India-rubber bands, a, which pass from one hook to the other, over the top of the rail A, and outside of the spring; as shown in fig. 2. It will thus be seen that each rail is secured upon the spring independent of the others; and can easily and readily be taken from the bedstead should it become broken.

Having thus fully described my invention, what I claim as new, and desire to secure by Letters Patent, is—

The combination and arrangement of the slat A with block D, and rail B with its hooked nails x x and d, with coil-spring C and strap a, when constructed and used in the manner and for the purposes specified.

In testimony that I claim the foregoing, I have hereunto set my hand this 22d day of April, 1867.
